W. F. Quinby,

Aerial Navigation.

N° 33,797.

Patented Nov. 26, 1861.

UNITED STATES PATENT OFFICE.

W. F. QUINBY, OF STANTON, DELAWARE.

IMPROVED APPARATUS FOR NAVIGATING THE AIR.

Specification forming part of Letters Patent No. 33,797, dated November 26, 1861.

To all whom it may concern:

Be it known that I, W. F. QUINBY, of Stanton, in the county of New Castle and State of Delaware, have invented certain new and useful Improvements in Apparatus for Navigating the Air; and I do hereby declare that the following is a full, clear, and exact description of the same, reference being had to the accompanying drawings, forming part of this specification, in which—

Figure 1 is a longitudinal vertical section of an aerial ship with my improvements applied. Fig. 2 is a transverse vertical section of the same.

Similar letters of reference indicate corresponding parts in both figures.

This invention consists in the use of oscillating wings of improved construction attached to the sides of a boat-like car for causing it to ascend, maintaining it at a given elevation, or regulating its descent in the air as may be desired; also in a certain arrangement, in combination with such wings, of a screw-propeller for giving the car a movement in a horizontal direction, and of spiral-bladed wheels like screw-propellers for assisting the side wings in producing the ascent, maintaining the elevation, or regulating the descent of the car.

To enable others to make and use my invention, I will proceed to describe its construction and operation.

The boat-like car is composed of a light frame *a a*, of wood or other suitable material, so constructed and braced by transverse and longitudinal braces *b b* and *c* as to obtain great strength with little weight, and covered up as high as desirable with oiled silk or other suitable light material. The oscillating wings, of which one pair only is represented, but of which there may be one, two, or more pairs, are composed each of an oblong frame *A*, of wood or other strong light material, fitted with a sufficient number of valve-like flaps *d d* to cover its entire area, such flaps being composed of light frames of wood or whalebone or other light elastic material having oiled silk or other suitable fabric stretched upon them, such flaps being arranged to open by an upward and to close by a downward movement. Of each pair of wings one is arranged on one side and the other on the other

side of the car, and both are attached rigidly to the same shaft *B*, a prolongation of whose axis would intersect them at the middle of their length and at right angles to their sides, the said shaft being arranged transversely to the length of the car in suitable bearings in the sides thereof, and the wings being so arranged upon the said shaft that both occupy the same plane or planes.

The screw-propeller *C* for propelling the ship in a horizontal direction is fast upon the main shaft *D*, which is arranged lengthwise of the car in a central position, the propeller being either in rear of the car, as represented, or in front thereof, or there being one in front and one in the rear of the car. The main shaft *D* may be driven by a small steam-engine, by manual labor, or by any other suitable means. The drawings represent a spring *E*, applied for the purpose of driving it. The said shaft carries a cam *F* for giving the necessary oscillating movement to the wing-shaft *B*, and two gears *G G'* for driving the upright shafts *H H'* of the two spiral-bladed wheels *I I'*, which assist the wings in controlling the ascent and descent and elevation of the ship.

The cam *F* acts to produce a vertical reciprocating movement of the yoke *J**, which slides in vertical guides *e e*, and this yoke is connected with an arm *f* on the wing-shaft *B*, so that by the reciprocating movement of the yoke an oscillating movement of said shaft to the extent of about a quarter of a revolution back and forth is produced, causing the wings to vibrate between two positions at angles of about forty-five degrees to the horizon, and causing them to be in a horizontal position when the yoke is at the middle of its stroke. The flaps *d d* of that part of each wing which is moving downward are always closed, so that they exert a downward pressure on the air, which tends to raise the car; but the flaps of the ascending portion of each wing are always opened by the pressure of the air, so that they offer no material obstruction to the ascent of the ship which may be caused by the oscillating movement of the wings to ascend to be sustained at a certain elevation or to merely have its descent checked and controlled according to their area and the velocity at which they are driven. When

the screw-propeller C is at work and the ship is intended to move horizontally, the wings may be stopped and locked at an upward inclination of about twenty-three and a half degrees in a forward direction, in which position they will, while the ship is being propelled forward, be so caused to press upon the air with their flaps d d all closed that a certain tendency to lift the car will be developed. When it is desired that the ship shall descend, the wings may be locked in a horizontal position, in which position they will tend to check the too rapid descent.

The spiral-bladed wheels I I' both have their shafts H H' arranged in the center of the car—that is to say, midway between its sides. The said wheels are of uniform size, but have the inclination of their blades in opposite directions, and consequently must rotate in opposite directions, the directions being always such as to exert a tendency to assist the wings in their operation, viz., to exert a tendency to counteract the effect of gravitation on the ship—that is to say, to raise it, sustain it at a given elevation, or check and control its descent according to their size and the velocity at which they are driven. The said wheels derive motion from the main shaft through gears J J' on their shafts H H' gearing with the gears G G' on the main shaft. The blades of the wheels I I' and those of the

screw-propeller C are all made of tight frames of wood or other material having oiled silk or other suitable fabric stretched on them.

L is a mast standing up between the shafts G G' at about in the lateral center and at about the middle of the length of the car for the attachment of a parachute M, which will be caused to spread itself when the car is descending, and so prevent the too rapid descent of the ship. The said mast has also fitted to turn on its lower part the rudder N, which consists of a long frame of wood or metal covered with oiled silk or other suitable fabric, and which is to be worked by ropes at the command of a person within the car for the purpose of steering the car.

What I claim as my invention, and desire to secure by Letters Patent, is—

1. The employment, in combination with the boat-like car, of oscillating wings A d d, constructed and applied to operate substantially as and for the purpose herein set forth.
2. The combination of the wings A d d, the screw-propeller C, and the spiral-bladed wheels I I', the whole operating together substantially as and for the purposes herein specified.

W. F. QUINBY.
